UNITED STATES PATENT OFFICE.

EUGENE J. MOYNIHAN, OF SAN FRANCISCO, CALIFORNIA.

EXCAVATOR-BUCKET.

1,307,747.

Specification of Letters Patent. Patented June 24, 1919.

Application filed July 13, 1918. Serial No. 245,775.

To all whom it may concern:

Be it known that I, EUGENE J. MOYNIHAN, a citizen of the United States, residing in the city and county of San Francisco, State 5 of California, have invented a new and useful Improvement in Excavator-Buckets, of which the following is a specification.

My invention relates to improvements in excavator buckets wherein a grating operates in conjunction with the bucket to separate fine from coarse material therein; and the objects of my invention are—

First, to provide an improved excavator bucket wherein fine may be separated from 15 coarse material during the excavating and conveying process;

Second, to provide an improved bucket of the character described having means for separating the bucket into upper and lower 20 compartments and screening the contents of the upper compartment;

Third, to provide an improved bucket of the class described wherein the contents of the lower compartment may be discharged 25 independently of the upper compartment and by the same tripping means;

Fourth, to provide a bucket of the class described wherein the lower compartment is arranged to permit a full discharge there- 30 through of the contents from the upper compartment.

I accomplish these several objects by means of the device disclosed in the drawings forming a part of the present specification where- 35 in like characters of reference are used to designate similar parts throughout the said specification and drawings, and in which—

Figure 1 is a side elevation of my im- 40 proved separating bucket;

Fig. 2 is a plan view of Fig. 1;

Fig. 3 is a vertical sectional view taken on line 3—3 of Fig. 2 in the direction indicated;

Figs. 4, 5 and 6 are enlarged detailed 45 views of an antifriction retaining latch used in connection with the bucket, Fig. 6 being a sectional view on line 6—6 of Fig. 4;

Fig. 7 is a vertical sectional view of a 50 bucket having both upper and lower com- partments filled;

Fig. 8 is a similar view disclosing the lower compartment discharged; and

Fig. 9 is an enlarged broken vertical sec- 55 tional view taken on line 9—9 of Fig. 2.

Referring to the drawings the numeral 1 is used to designate in general an excavator

bucket comprising a single front piece 2 having the usual teeth 3 on the upper end thereof and provided with latch apertures 4 and 6. 60

The bucket 1 comprises upper and lower sections, said upper section being composed of rearwardly extending lateral extensions 7 formed integral with the upper portion of the front piece 2 and an inner U-shaped 65 member 8 having forwardly extending lateral extensions 9 which are secured to the extensions 7 of the front piece 2, as disclosed in Fig. 2 of the drawings.

A pair of oppositely offset members 11 are 70 secured to the outer surfaces of the extensions 7 of the front pieces 2 and by means of a suitable pin 12 have their rear ends connected by links 14 to a suitable bearing plate 16 on the end of a dipper or bucket 75 handle 18.

The back of the upper section is further secured to the dipper handle 18 by means of a plate or member 19 and a pin 20 mounted within suitable bearings upon the rear 80 of said upper section. From the pin 20 a single bar 21 is hingedly suspended which, when in a closed position, extends nearly to the latch aperture 4 in the front piece 2.

A grating 22 is rigidly secured to on top 85 of the bar 21 and when closed with the bar 21 operates to separate the bucket 1 into upper and lower compartments, said compartments comprising a lower section which consists of a U-shaped member 26 secured 90 to the front piece 2 and having rearwardly extending extensions 27 slightly greater in width than the rearwardly extending extensions 7 of the front piece 2, the purpose of which will hereinafter be more fully set 95 forth.

A second U-shaped member 28 is pro- 100 vided with forwardly extending extensions 29 which are rigidly secured to the exten- sions 27 of the member 26. The extensions 29 are in turn provided with upwardly ex- 105 tends or vertically disposed extensions 31 by means of which the entire lower section comprising the members 26 and 28 may be secured rigidly to the upper section of the bucket 1.

The rear portion of the member 28 is ex- 110 tended beyond the rear of the member 8 a greater distance than the extensions 27 ex- tend beyond the extensions 7 so as to pro- vide a space within which the grating 22 may swing clear of the opening through the

upper section of the bucket 1 thereby permitting a free and full discharge of the full capacity of the said upper section when said grating 22 is opened.

5 To the rear of the U-shaped member 28 are integral lugs 32 rotatably supporting a pin 33 from which is suspended a door 34 to close the lower section or compartment of the bucket 1.

10 The grating 22 and door 34 are provided with retaining latches 36 and 37 respectively, which latches are described and claimed in a copending application. The latches 36 and 37 are arranged to engage the latch apertures 4 and 6 respectively in the front piece 2 when closed and thereby form upper and lower compartments.

15 A tripping lever 38 is suspended from the dipper handle 18 by means of a suitable eye-let 39 and a short chain or other suitable connection 41 extends from the said tripping lever 38 to the latch 37 on the hinged door 34 while a longer connection 42 extends from the tripping lever 38 to the latch 36 of the grating 22 passing over a suitable roller or sheave 43, rotatably mounted on the back of the lower section, and passing through an aperture 44 in the member 28. The connection or chain 42 is provided with an obstruction 46 in the shape of a larger link which limits the passage of the chain 42 through the aperture 44 when the grating 22 is closed thereby preventing said chain 42 from becoming fouled or entangled with the contents of the lower compartment which might tend to trip the latch 36 prematurely when the door 34 is released or opened.

20 A bail 47 is provided by means of which the bucket may be raised and lowered and operated.

25 A tripping line 48 is secured to the lower end of the tripping lever 38 by means of which said lever 38 may be operated.

30 By the arrangement of the members 2, 7, 8 and 11 of the upper section with the members 26, 27, 28, 29 and 31 secured to said upper section by means of the extensions 31 it will be observed that I have provided a rigid, compact construction which will impart rigidity and strength to the entire structure and thereby provide an efficient bucket having two compartments of which the upper one is the smaller for the reason that the extensions 27 extend slightly beyond the extensions 7 of the front piece 2 while the back or U-shaped portion 28 of the lower section is extended a greater distance beyond the rear of the U-shaped member 8 of the upper section. This arrangement therefore provides a two-compartment bucket separated by the grating 22 whereby finer material may be separated from the coarser or boulders and conveyed to separate conveyors in the following manner:

35 The bucket is operated in the usual well

known manner to scoop a load of earth, mixed gravel or other similar material.

As the bucket 1 is raised to a horizontal position the smaller particles, such as gravel or loose earth, readily passes through the 70 grating 22 into the lower compartment while larger pieces of earth or rocks, boulders and the like, are retained above the grating.

The bucket 1 is then moved to a position over a car or other conveyer A and the tripping line 48 is operated to release or trip the latch 37 and thereby release the door 34 which will then swing open by gravity and discharge the smaller material into said conveyer A.

30 The latch 36 of the grating 22 will not be tripped simultaneously with the tripping of the latch 37 for the reason that the connection 41 to the latch 37 of the door 34 is shorter than the connection 42 to the latch 36 of the grating 22. Therefore as soon as the door 34 is opened the tension on the line 48 is released until the bucket 1 is moved over a second car or conveyer B to receive the larger material as is disclosed in Fig. 8 90 of the drawings.

35 The tripping line 48 is again operated to release or trip the latch 36 of the grating 22 and said grating 22 then swings into the space provided by the extension of the member 28 beyond the member 8 as hereinbefore described and clear of the upper section or compartment thereby readily permitting a free and full discharge of the full capacity of said upper section or compartment.

40 When both compartments have been discharged or emptied and the bucket 1 lowered to receive the next load the door 34 and grating 22 are closed by the action of gravity and the latches 36 and 37 engage their respective apertures 4 and 6 in the front piece 2.

45 It is obvious that from the foregoing that I have provided an improved separating bucket separated into compartments as well as improved means for discharging the contents of said compartments independently of each other.

50 Having thus described my invention what I claim as new and desire to secure by Letters Patent is—

55 1. The combination with a receptacle of a grating hingedly mounted therein to divide said receptacle into upper and lower compartments; and a door hingedly mounted upon the receptacle to close the lower compartment.

60 2. The combination with a receptacle of a grating hingedly mounted therein to divide said receptacle into upper and lower compartments; a door hingedly mounted upon the receptacle to close the lower compartment; and means for tripping the door previously to tripping the grating.

65 3. A receptacle comprising upper and

- lower sections, the back of the lower section extending slightly beyond the back of the upper section; a grating hingedly mounted upon the back of the upper section and arranged to separate the receptacle into upper and lower compartments and to swing into the extension of the lower section; a door hingedly mounted upon the back of the lower section and arranged to close the bottom of said section; and suitable latches secured to the grating and to the door to retain the same in a closed position. 5
4. A receptacle comprising upper and lower sections, the back of the lower section extending slightly beyond the back of the upper section; a grating hingedly mounted upon the back of the upper section and arranged to separate the receptacle into upper and lower compartments and to swing into the extension of the lower section; a door hingedly mounted upon the back of the lower section and arranged to close the bottom of said section; suitable latches secured to the grating and to the door to retain the same closed position; and means for tripping the latch of the lower door independently of the grating. 10
5. A receptacle comprising upper and lower sections, said lower section extending back of the upper section and having lugs formed integral therewith whereby said lower section may be secured to the upper section; a grating hingedly mounted to the receptacle and arranged to form upper and lower compartments within the bucket when said grating is closed and to swing into the extension of the lower section when opened thereby permitting a discharge of the full capacity of the upper compartment when open; a door hingedly mounted to close the lower section; suitable latches secured to the door and grating to retain the same in a closed position; and means for tripping door latch independently of and previously 15 to the grating latch whereby the lower compartment may be emptied without disturbing the contents of the upper compartment. 20
6. The combination with a dipper handle of an excavator bucket secured thereto and having upper and lower sections, said lower section extending slightly back of the upper section; a grating hingedly mounted upon the bucket and arranged to separate said bucket into upper and lower compartments when closed and to swing into the extension of the lower section when open to permit a full discharge of contents from the upper section; a door hingedly mounted to close the lower section; suitable latches 25 mounted upon the door and grating; a tripping lever suspended from the dipper handle adjacent the bucket; a connection from the lever to the grating; and a shorter connection from the lever to the door whereby the latch on the door may be released previously to the latch on the grating when the lever is operated. 30
7. The combination with a dipper handle of an excavator bucket secured thereto and having upper and lower sections, said lower section extending slightly back of the upper section; a grating hingedly mounted upon the bucket and arranged to separate said bucket into upper and lower compartments when closed and to swing into the extension of the lower section when open to permit a full discharge of contents from the upper section; a door hingedly mounted to close the lower section; suitable latches 35 mounted upon the door and grating; a tripping lever suspended from the dipper handle adjacent the bucket; a connection from the lever to the grating; and a shorter connection from the lever to the door whereby the latch on the door may be released previously to the latch on the grating when the lever is operated; and means for preventing the slack of the longer connection to the grating latch from sliding into the lower section when the grating is closed. 40
8. The combination with a dipper handle of an excavator bucket secured thereto and having upper and lower sections, said lower section extending slightly back of the upper section; a grating hingedly mounted upon the bucket and arranged to separate said bucket into upper and lower compartments when closed and to swing into the extension of the lower section when open to permit a full discharge of contents from the upper section; a door hingedly mounted to close the lower section; suitable latches 45 mounted upon the door and grating; a tripping lever suspended from the dipper handle adjacent the bucket; a connection from the lever to the grating; and a shorter connection from the lever to the door whereby the latch on the door may be released previously to the latch on the grating when the lever is operated; and means for preventing the slack of the longer connection to the grating latch from sliding into the lower section when the grating is closed; and means for operating the tripping lever. 50

In witness whereof I hereunto set my signature.

EUGENE J. MOYNIHAN.
